[57] CLAIM

The ornamental design for an electronic copying machine or the like, substantially as shown and described.

DESCRIPTION

FIG. 1 is a perspective view of an electronic copying machine showing my new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof;

FIG. 7 is a front perspective view with the cover in an open position;

FIG. 8 is an enlarged top-front perspective view of the upper portion of the machine with the display in a folded position.

FIG. 1
